UNITED STATES PATENT OFFICE.

WILLARD M. WHITMAN, OF BOSTON, MASSACHUSETTS.

DESIGN FOR A REFRIGERATOR.

SPECIFICATION forming part of Design No. 30,141, dated February 7, 1899.

Application filed May 28, 1898. Serial No. 682,072. Term of patent 14 years.

To all whom it may concern:

Be it known that I, WILLARD M. WHITMAN, a citizen of the United States, residing in Boston, in the county of Suffolk and State of Massachusetts, have invented and produced a new and original Design for Refrigerators, of which the following is a specification, reference being had to the accompanying drawing, forming a part thereof.

10 In the drawing a refrigerator embodying the essential elements of my design is shown.

As shown in the drawing, the design embraces the base A, which is substantially rectangular and which is ornamented by panels,

15 the intermediate section B, which embraces a rectangular rear part and the curved glass

front b, which is bowed from the upper front edge of the said section downwardly and outwardly, and the upper section C, which is rectangular in shape and which has also the 20 curved glass front c, bowed forwardly from each side on a horizontal arc.

Having described my invention, what I claim as new, and desire to secure by Letters Patent of the United States, is—

25 The design for a refrigerator as herein shown and described.

WILLARD M. WHITMAN.
